UNITED STATES PATENT OFFICE

ALLEN B. PIERCE, OF SYRACUSE, NEW YORK, ASSIGNOR TO THE PROSPERITY COMPANY, INC., OF SYRACUSE, NEW YORK, A CORPORATION OF NEW YORK

ACTUATING MECHANISM FOR PRESSING MACHINES

Application filed December 3, 1924. Serial No. 753,557.

This invention relates to pressing machines and has for its object a particularly simple and efficient actuating mechanism for the movable elements or press heads of such machines whereby the leverage between the prime mover and the power arm or treadle is increased during the closing of the press, that is, so that the leverage is greatest when final pressure is being applied to the press head so that less effort is required to apply final pressure.

The invention consists in the novel features and in the combinations and constructions hereinafter set forth and claimed.

In describing this invention, reference is had to the accompanying drawing which is a side elevation, partly broken away, of a machine embodying my invention, the position of the actuating mechanism when the press head is open being shown in broken lines and when the press is closed in full lines.

This pressing machine comprises a frame, a movable press head, a movable support for the press head, an actuating mechanism including a prime mover as a power arm or treadle, motion transmitting means between the prime mover and the support for the press head including means for changing the effective leverage of the prime mover or treadle to increase said leverage as the press head moves toward its closed position.

More specifically, the machine comprises a movable press head and means for supporting and actuating the press head including a lever and a link connected to the lever and shiftable in a radial direction relatively to the axis thereof and means for shifting said link during the opening and closing of the press. As here illustrated, the supporting and actuating means comprises a lever supporting the press head, a power lever or treadle pivoted to the frame, intermediate motion transmitting mechanism including a lever pivoted between its ends to the frame, a link connecting one arm of the lever to the supporting lever and a link connecting the other arm of the intermediate lever to the treadle, one of said links being shiftable in a radial direction relatively to the axis of one

of the levers it connects during the opening and closing of the press and means for shifting such shiftable link during the opening and closing of the press.

I have here illustrated my invention as embodied in a standard pressing machine including a suitable frame 1, a lower stationary buck 2 and a press head 3 usually carried by a yoke or lever 4 pivoted at 5 between its ends to a standard 6 rising from the frame. The frame may be of any suitable form, size and construction.

The buck 2 is mounted on a suitable standard or goose neck 7 rising from the frame 1 or the table 8 thereof. The yoke 4 is usually provided on the rear arm thereof with a weight 9 and also springs as 10 are connected to such rear arm, the weight 9 and springs 10 serving to counter-balance the head 3 and to open the press.

11 is a prime mover or a power arm or lever, as a treadle pivoted at 12 at its rear end and having a foot plate 13 at its front end. The motion transmitting means between the treadle 11 and the yoke 4 comprises an angle lever 14 pivoted at its angle at 15 to the frame at a point located above the lever 11 and in front of the vertical plane of the axis 12 of the lever, a link 16 pivoted at one end at 17 to the rear arm of the angle lever 14 and at its other end at 18 to the rear arm of the yoke or press head supporting lever 4, the link 16 forming a toggle with the rear arm of the angle lever 14, and a link connecting the lever or treadle 11 and the forward arm of the angle lever 14. Means is provided for shifting the link radially relatively to the axis of one of the levers it connects as the press is closed and opened for changing the effective leverage of the power lever on the press head. The toggle is formed with a stop joint to limit the movement of the link 16 and the angle lever 14 when they are in, or nearly in, a straight line.

The link 19 here shown, is shiftable relatively to the axis 15 of the angle lever 14 and is pivoted at its front end at 20 to the pedal lever 11 and at its other end to the forward arm of the angle lever 14, this link 19 inclining downwardly and forwardly from

the angle lever and being shiftable relatively to the axis of the angle lever. As here illustrated, the forward arm of the angle lever 14 is formed with a lengthwise curved slot 21 extending in a general radial direction for receiving the pivot 22 of the link 19.

The link 19 is shifted during the closing and opening movement of the press radially relatively to the axis of the angle lever 14 by means here illustrated as a link 23 pivoted at its rear end at 24 to the frame and at its front end to the link 19, it being preferably mounted on the same pivot 22 that connects the link 19 and the forward arm of the angle lever 14. The pivot 24 of the link 23 is located between the pivot 15 of the lever 14 and the power lever 11 and is located in nearly a vertical line with the pivot 15 of the angle lever 14 and such link 23 inclines upward and forward.

The angle lever 14 and the toggle link 16 are so arranged that when the press head is open, the toggle link 16 is in nearly an upright position and approximately at a right angle to the rear arm of the angle lever 14 as indicated in dotted lines so that upon the initial depression of the treadle 11, the thrust on the yoke lever 4 is vertically upward. Also when the press is open, the pivot 22 of the link 19 is located near the inner end of the slot 21 or nearest the axis 15 of the angle lever 14 as indicated in dotted lines.

There are preferably two springs 10 arranged parallel to each other and the angle lever 14 and toggle link 16 moves between such springs when the press is open also the treadle lever 11 extends between such springs.

When the press head is open, very little power is needed to start it toward its closed position and at this time the leverage is least and a relatively small movement of the treadle 11 swings the open press head toward closed position. During the movement of the press head toward closed position, the link 19 is shifted along the forward arm of the power lever 14 toward the outer end thereof, thus increasing the leverage so that when the final pressure is to be applied, motion of the treadle 11 through the greater leverage is converted into power, that is, a greater relative movement of the treadle is required to exert pressure to bring the toggle into a straight line, than is required to initially close the press head.

At the starting of the closing movement, power on the treadle is converted into rapid motion of the press head and during the latter movement of the treadle, motion or distance of travel of the treadle 11 is converted into power.

Owing to the arrangement of the angle lever and the toggle a lever having a short throw compared with types of toggle heretofore used can be employed.

What I claim is:

1. In a pressing machine, the combination of a frame, a movable press head, a lever supporting said head, the lever being pivoted to the frame, actuating mechanism comprising a pivoted power arm, an angle lever pivoted to the frame, a link pivoted at one end to one arm of the angle lever and at its other end to the supporting lever for the press head, the link forming a toggle with such arm of the angle lever, and a second link pivoted at one end to the power arm and at its other end to the other arm of the angle lever and means for changing the effective leverage of the power arm on the supporting lever during the movement of the power arm.

2. In a pressing machine, the combination of a frame, a movable press head, a lever supporting said head, the lever being pivoted to the frame, actuating mechanism comprising a pivoted power lever, an angle lever pivoted to the frame, a link pivoted at one end to one arm of the angle lever and at its other end to the supporting lever for the press head, the link forming a toggle with said arm of the angle lever, and a second link pivoted at one end to the power lever and at its other end to the other arm of the angle lever by a sliding joint movable lengthwise of the arm of the angle lever to which the second link is connected and means for moving the last mentioned link toward and from the axis of one of the levers it connects as the power lever is operated to open or close the press.

3. In a pressing machine, the combination of a frame, a movable press head, a lever carrying said head, the lever being pivoted to the frame, actuating mechanism comprising a power lever, an angle lever pivoted to the frame, a link pivoted at one end to one arm of the angle lever and at its other end to the supporting lever for the press head, the link forming a toggle with said arm of the angle lever, and a second link pivoted at one end to the power lever and at its other end to the other arm of the angle lever by a sliding joint movable lengthwise of the arm of the angle lever to which the second link is connected, and means for moving the second mentioned link radially relatively to the axis of the angle lever during the operation of the power lever.

4. In a pressing machine, the combination of a frame, a movable press head, a lever carrying said head, the lever being pivoted to the frame, actuating mechanism comprising a pivoted power lever, an angle lever pivoted to the frame, a link pivoted at one end to one arm of the angle lever and at its other end to the supporting lever for the press head, the link forming a toggle with said arm of the angle lever, and a second link pivoted at one end to the power lever and at its other end to the other arm of the angle lever.

lever, the last mentioned arm of the angle lever being formed with a lengthwise slot and the link connecting said arm and the power lever having its pivot movable along said slot and means for shifting the pivot along the slot during the operation of the power arm.

5. In a pressing machine, the combination of a frame, a movable press head, a lever carrying said head, the lever being pivoted to the frame, actuating mechanism comprising a power lever, an angle lever pivoted to the frame, a link pivoted at one end to one arm of the angle lever and at its other end to the supporting lever for the press head, the link forming a toggle with said arm of the angle lever, a second link pivoted at one end to the power lever and at its other end to the other arm of the angle lever by a sliding connection 10 extending lengthwise of said other arm of the angle lever and a link pivoted at one end to the frame and connected at its other end to the link connecting the angle lever and the power arm.

25. In a pressing machine, the combination of a frame, a movable press head, a supporting lever for the press head pivoted between its ends to the frame, a power arm pivoted to the frame near the lower end thereof, an angle lever pivoted to the frame above the power arm and in front of the vertical plane of the axis of the power arm, a link pivoted at one end to the rear arm of the angle lever and at its other end to the rear arm of the 30 supporting lever and forming a toggle with the angle lever, the link being normally arranged to stand at an angle approximating a right angle to the arm of the angle lever to which it is pivoted when the press is open 35 and a link connecting the other arm of the angle lever and the power arm, the arms of the lever being arranged at approximately a right angle to each other, the link being movable radially relatively to the axis of one of 40 the levers it connects and means for moving the same during the opening and closing of 45 the press.

7. In a pressing machine, the combination of a frame, a movable press head, a supporting lever for the press head pivoted between its ends to the frame, a power lever pivoted at its rear end to the frame near the lower end thereof, an angle lever pivoted to the frame above the power lever and in front of 50 the vertical plane of the axis of the power lever, a link pivoted at one end to the rear arm of the angle lever and at its other end to the rear arm of the supporting lever and forming a toggle with the angle lever, the 55 link being normally arranged to stand when the press is open at an angle approximating a right angle to the arm of the angle lever to which it is pivoted, the other arm of the angle lever being formed with a lengthwise slot, a link pivoted at its lower end to the

power lever and at its upper end to the angle lever, the pivot at the upper end of such link being movable in said slot and means for moving it in the slot during the opening and closing of the press.

8. In a pressing machine, the combination of a frame, a movable press head, a supporting lever for the press head pivoted between its ends to the frame, a power lever pivoted at its rear end to the frame near the lower end thereof, an angle lever pivoted to the frame above the power lever and in front of the vertical plane of the axis of the power arm, a link pivoted at one end to the rear arm of the angle lever and at its other end to the rear arm of the supporting lever and forming a toggle with the angle lever, the link being normally arranged to stand when the press is open at an angle approximating a right angle to the arm of the angle lever to which it is pivoted, the other arm of the angle lever being formed with a lengthwise slot, a link pivoted at its lower end to the power lever and at its upper end to the angle lever, the pivot at the upper end of said link being movable in said slot, and a link pivoted at its rear end to the frame below the pivot of the angle lever and at its front end to the link connecting the angle lever and the power arm.

9. In a garment pressing machine having a self-opening press head, toggle-connections between the press head and the frame of the machine, an extension-bearing on one of the toggle members in front of the toggle-joint and above the connection of the toggle with the frame and a pedal-operated lever having means to engage said bearing at gradually increasing distances from the connection of the toggle with the frame for straightening the toggle to force the press head to its pressing position.

In testimony whereof, I have hereunto signed my name, at Syracuse, in the county of Onondaga, and in the State of New York, this 22nd day of November, 1924.
